UNITED STATES PATENT OFFICE.

RALPH G. A. BECK, OF MONTREAL, QUEBEC, CANADA.

NURSING BOTTLE AND THE LIKE.

Application filed March 21, 1927. Serial No. 177,035.

This invention relates particularly to infants' nursing bottles and the like and nipples or teats therefor, and has for its object primarily the provision of a new and improved construction and arrangement of the parts whereby the nipple may be snugly interlocked with the bottle neck when fitted over the mouth thereof for the purpose of obviating leakage at this point and preventing accidental displacement of the nipple when in use.

Heretofore many attempts have been made to produce a nursing bottle nipple which would not accidentally come off the bottle when in use and while some have in a measure been successful, none have provided an entirely satisfactory solution of the problem.

A further object of the invention is to provide a nursing bottle nipple having means forming an integral and component part thereof for facilitating the application of the nipple to and its removal from the bottle neck. Such a means is particularly desirable in modern nipples or teats of the band type which adhere tenaciously to the bottle and present a comparatively smooth exterior which is extremely difficult to grasp.

A further object of the invention is to provide a nursing bottle having new and improved means for preventing it from rolling when placed on its side.

Other objects are to provide a nursing bottle which owing to its peculiar shape can be thoroughly cleansed with comparative ease, and which can be manufactured at reasonable cost.

To this end my invention consists of the construction and arrangement of the parts hereinafter described and illustrated and pointed out in the claim.

In the accompanying drawings in which similar reference characters indicate the same parts:

Figure 1 is a side elevation of a nursing bottle constructed according to my invention;

Figure 2 is a fragmentary part elevation and part sectional view of the bottle neck with the nipple or teat mounted thereon;

Figure 3 is a sectional view taken on line 3—3 Figure 1; and

Figure 4 is a detail elevation of the nipple partly in section.

Referring to these drawings which illustrate the preferred embodiment of my in-

vention the bottle proper is indicated at 2 and the nipple at 3.

The body of the bottle is preferably of round cross-section, as indicated in full lines 60 in Figure 3, or elliptical, as indicated in dotted lines in the same figure, and is provided with a flat external bottom surface 4 to permit it to be placed in upright position, as indicated in Figure 1, the external 65 surface 5 of the side wall being extended downwardly to the bottom surface at right angles thereto so that a wide bearing area equal to the full cross-section of the bottle is provided.

To facilitate the cleansing of the bottle its entire internal surface area is free from corners, ridges or obstructions of any kind. To this end the internal surface 6 of the side wall extends parallel to the external surface 70 thereof from the bottle neck to a point a short distance from its bottom, from which point it curves inwardly to form a concavity 7 constituting an internal bottom. The interior of the bottle thus shaped is of a deep 75 bowl-like formation, the concaved bottom merging with the elongated sides and co-acting therewith in providing an unbroken internal surface. This construction and arrangement facilitates cleansing, permits 80 the bottle to be placed on its end in an upright position for filling or any other purpose, and locates sufficient weight in its bottom end to reduce to a minimum the danger 85 of the bottle falling over when in such position.

In order to provide means for preventing the bottle from rolling when placed on its side the body is provided with external longitudinal ribs 8 which project outwardly a 90 sufficient distance to enable them to function as stops adapted to limit a rolling movement. If the bottle is of circular cross-section it is 95 preferably provided with three ribs arranged equi-distantly apart, as indicated in Figure 3. If, on the other hand, the bottle is of elliptical cross-section, two ribs are 100 preferable. Although an elliptical bottle has not so much tendency to roll as the circular type it will roll under certain conditions encountered in actual use, and the provision of the ribs as suggested will be found 105 to be of distinct advantage in maintaining the bottle in the desired location. The ribs should be so shaped that they will be free 110 from sharp corners or edges. In the embodiment illustrated they are rounded in

cross-section and their extreme ends slope gently towards the external surface of the bottle as indicated at 8^a.

The upper portion of the bottle is curved inwardly at 9 on a wide radius and terminates in a comparatively short neck 10 having an orifice or mouth 12 over which the rubber nipple is positioned.

Heretofore the nipple has been the source of constant trouble owing to its tendency to come off when in use, or to become so displaced as to cause leakage, and many attempts have been made to provide a solution of the problem. To my knowledge, however, none have proved entirely satisfactory and much difficulty is still being experienced with the various types of nipples now in use. The present invention seeks to overcome the problem by so constructing the bottle neck and the nipple that one will interlock with the other in such a manner that the possibility of the nipple becoming accidentally dislodged or displaced is positively prevented. In fact with the construction and arrangement of the parts hereinafter described it is impossible to pull the nipple off the bottle if it is grasped at its free end. The preferred embodiment for securing the foregoing desideratum consists of a pair of vertically spaced external collars 14 and 15, respectively, formed integrally with the bottle neck and encircling the same at the mouth thereof, and a pair of correspondingly spaced internal continuous beads 16 and 17 formed integrally with a skirt or band 18 on the nipple. This skirt or band consists of a comparatively thin elastic sleeve-like extension joined to the bottom edge of and being of smaller diameter than the breast or shoulder portion 19 of the nipple and adapted to be stretched over the bottle neck, the band, when in position, snugly conforming to the irregular shape presented by the collars and extending downwardly for a short distance below the same. In order to obtain the positive interlocking relationship hereinbefore referred to, the underside of each collar is recessed as at 20 in hooked form, and the dimensions and relative spacing of the beads on the nipple are such that when in position on the bottle the beads snugly fit within the recesses. It is obvious from this construction and arrangement of parts that any direct pull on the nipple away from the bottle will simply cause the nipple to grip the bottle more tightly. The interlocking relationship is clearly shown in section in Figure 2 and it will be noted that owing to the inherent elasticity of the band and the breast or shoulder portion the nipple snugly adheres to the rounded external surfaces of the collars indicated at 14' and 15' respectively so that a snubbing action at these points is obtained which further assists in preventing dislodgment of the beads from

their respective grooves. The top collar 14 is rounded off as at 14^a to facilitate the application of the nipple and merges with the bottle neck to form a flared mouth. The lower collar 15 does not project outwardly as far as the top collar, nor is its recess as deep, and its external surface is inclined upwardly and inwardly to the top recess as indicated at 21. The lower collar consequently tapers upwardly to the top collar in frusto-conical form so that if the lower nipple bead should become sufficiently displaced to slip over the lower collar it will slide along the inclined face 21 into the top recess. The beads are of substantially half-round cross-section and are respectively located at the junction of the top edge of the band and the bottom edge of the breast or shoulder portion of the nipple and at a point a short distance below the same on the inner face of the band.

In view of the fact that the collars project beyond the normal exterior of the neck and that the nipple positively interlocks therewith it is desirable to provide means for facilitating the application of the nipple and its removal from the bottle. To this end the band has integrally formed therewith downwardly extending lips 22 and 23 constituting fingerholds which may be grasped in the applying and removing operations. These lips are located diametrically opposite one another and terminate in thickened edges 24.

In applying a nipple or teat constructed according to my invention one of the lips is clamped against the bottle neck with the forefinger of one hand while the band is distended sufficiently, by grasping the other lip with the other hand, until it can be pulled over the collars to position in which the beads lie snugly within the recesses. In the removal operation it is only necessary to grasp either one of the lips and peel it backward until the beads clear the collars.

Although this invention is primarily designed for use in connection with nursing bottles and the like it is to be distinctly understood that it may be embodied in other receptacles of like nature without departing from the spirit of the invention.

In certain types of bottles detachable rubber valves are fitted over valvular openings in the bottles at or adjacent to their bottom ends and it is obvious that the application of the interlocking feature and the fingerholds thereto is within the scope of the present invention.

The nursing bottle nipple per se is not claimed herein as the same forms the subject matter of a separate application forming a divisional part of this case.

What I claim is as follows:

A nursing bottle having a neck terminating at its mouth in an external collar of hooked cross-section presenting a recess in

its underside, and a nipple or teat fitted over the said mouth and having a breast portion and a sleeve-like extension constituting a band adapted to encircle the bottle neck at 5 and below the said collar and being of smaller diameter than the breast portion and having an inwardly projecting bead extending into the recess in the collar and interlocking therewith, said bead being inwardly

removed from the bottom edge of the band, 10 and a tab-like fingerhold constituted by an integral portion of the band extended downwardly from the bottom edge of the band, substantially as described.

Signed at the city of Montreal, Province ¹⁵ of Quebec, this 17th day of March, 1927.

RALPH G. A. BECK.
